UNITED STATES PATENT OFFICE.

WILLIAM S. WELLS, OF SOUTH BETHLEHEM, PENNSYLVANIA.

LOOM.

1,319,196.

Specification of Letters Patent. Patented Oct. 21, 1919.

Application filed April 25, 1918. Serial No. 230,661.

To all whom it may concern:

Be it known that I, WILLIAM S. WELLS, a citizen of the United States, residing at South Bethlehem, in the county of Lehigh and State of Pennsylvania, have invented certain new and useful Improvements in Looms, of which the following is a specification.

This invention relates to looms, and it consists in certain improvements designed especially for the weaving of more or less tightly woven and heavy material, such as belting, where the shuttle or equivalent is best carried, and not merely thrown, through the shed and the beating-up action best involves quite a sharp blow to lay the filling properly up to the fell of the cloth. Besides including novel means, answering these requirements, for passing the filling into the shed and then beating it up, my invention comprehends certain other novel features, among which may be mentioned a filling replenishing means and a harness motion.

25 In the accompanying drawings,

Figure 1 is a front elevation of the improved loom;

Figs. 2 and 3 left and right side elevations, respectively;

30 Fig. 4 a plan;

Figs. 5 and 6 sectional views on the line 5—5, Fig. 4, showing parts of the harness motion in two different positions;

Fig. 7 is an enlarged fragmentary front elevation, illustrating the shuttle carrying and filling replenishing means and a part of the harness motion;

Fig. 8 is a sectional view of the shuttle carrier on line 8—8, Fig. 7;

40 Figs. 9 and 10 are sectional views of said carrier on line 9—9 Fig. 7, showing a certain part in two different positions;

Fig. 11 is a fragmentary side elevation illustrating the filling replenishing means;

45 Fig. 12 is a plan view of one of the shuttles, open;

Fig. 13 is a transverse sectional view of said shuttle, open, the filling package being removed;

50 Fig. 14 is a transverse sectional view of

said shuttle, closed, with the filling package in place;

Fig. 15 is a longitudinal sectional view of the shuttle and its receiver, the detector thereof being in position for the proper instrumentalities to accomplish filling-replenishing;

Fig. 16 shows the receiver in transverse section; and

Fig. 17 is a longitudinal sectional view of the filling package, the detector being shown retracted.

The frame includes a pair of side standards *a*—*a* and two other standards *b*—*b* projecting laterally from (in the present case) the right-hand side standard *a*. The several standards are suitably braced as shown in the drawings, some of the bracing parts being hereinafter indicated.

In brackets projecting from the rear standard *b* is journaled a horizontal drive shaft *c*, and in brackets projecting from both standards *b* is journaled a horizontal shaft *d*, shafts *c* and *d* being at right angles to each other and connected by bevel gearing *e* so as to rotate at the same speed. In brackets projecting from the standards *b* there is also journaled a cam shaft *f* parallel with shaft *d* and connected with the latter, so as to rotate at a speed-ratio of 1 to 2, by 70 the gearing *g*.

Each shaft *c* *d* is a part of a means for translating a rotary motion into a reciprocating motion in which the speed at one of the limits of the latter motion will be relatively quick. Thus, *h* is a face plate on the left hand end of shaft *c*; *i* is a pitman pivoted to a wrist pin *j* on the face plate; and *k* a lever fulcrumed in one of the side standards *a* and pivoted to a stud *l* on the pitman, the length of the pitman (from *j* to *l*) approximating but preferably somewhat exceeding the radius from the center of the face plate to *j*. Associated with the shaft *d* in a relation corresponding to that of the parts *h* to *l* (just mentioned) are the similar parts *h'*, *i'*, *j'*, *k'* and *l'*.

The lines A—, B—, C—, in Figs. 1 and 2 denote the elevations assumed by the points *l* and *l'* at the highest, lowest, and either 100

midway positions of the wrist pins j j' , respectively, in one cycle of rotation. The point l (or l') obviously performs its downward-and-back movement, between C and D, faster than it does its upward-and-back movement, between C and A, the first or downward half of the former movement being further an appreciably accelerating one—up to a point near the limit of such movement. The means described are therefore well adapted to produce, in effect, a whipping-up of the filling to the fell of the cloth and also a desirably quick picking or shuttle-thrust movement, the parts involved (the reed and shuttle as will appear) moving, moreover, relatively slowly while retracted.

Take-up and let-off mechanism.—A sand roller m is journaled at the front of the side standards a a and a guide roller n is journaled above it. A bracket o is fulcrumed in said side standards between the rollers m and n , and in it are journaled the rollers p , q , the latter of which bears on the former; a spring r normally presses the bracket upwardly. The cloth extends over roller n , around the sand roller m , and then between rollers p and q ; in coaction with the let-off mechanism, the sand roller preserves the desired tension, roller q , by being held by spring r pressing yieldingly against the cloth between m and n , permitting the give-and-take incident to the opening and closing of the shed. The sand roller shaft s carries at one end a worm wheel t which engages with a worm wheel u on a shaft v , journaled in the frame, which carries a ratchet wheel w and on which is fulcrumed a lever x connected with lever k' by a link y and equipped 40 with a pick awl z engaging the ratchet wheel.

2 is the warp beam and 3 the whip roll journaled at the back of the loom, the warp beam being provided with some suitable 45 rotation resisting medium, preferably a strap 4 which engages its periphery and has the end thereof corresponding to the direction in which the beam rotates connected to the frame by the spring 5 and the 50 other end wound around and suitably secured to the pulley 6 having a weighted arm 7.

Beating-up means.—The lay or batten structure, as herein shown, includes a single-lay-sword 8 fulcrumed on a cross shaft 9 connecting the standards a . Its head or lay proper has the reed 10 suitably secured thereto, as by bolts or screws 11 (Fig. 2). The lay-sword is connected with a lever 12 60 by the pitman 13, said lever being fulcrumed on a cross-shaft 14, connecting the side frames a , and being connected with the stud 17 by the link 15; adjustment of the throw of the lay-sword may be effected 65 by shifting the connections between 12 and

13 or 12 and 15, afforded by the holes 16 in lever 12 shown in Fig. 2.

Harness motion.—To the side standards a a are suitably secured the uprights 17—17, each having at its inner face a pair 70 of vertical ways or grooves in which slide the two rectangular harness frames 18—18. Clips 19, engaged with the top and bottom of each frame, support the harness 20 stretched therein. A pair of levers 21—21 75 are fulcrumed on a cross-shaft 22 connecting the side standards a , each being normally held depressed by a spring 23, and these levers are respectively connected with the harness frames 18 by the pitmen 24—24. 80 To obtain the alternate rise of the harness frames I employ the following mechanism: Suspended by a universal joint 25 from the lever k is a lifting hook 26 arranged between the levers 21—21 and having a hook 85 or stirrup 27 on each side thereof so that it is adapted to lift either lever on being swung sidewise. The lifting hook is normally pressed to the left by a spring 27' attached to a horizontal plate 28 in an opening in 90 which the lifting hook plays sidewise (Figs. 2, 3 and 4), and may be pulled to the right by a cam 29 on the cam shaft f against which bears a lever 30, suitably fulcrumed in the frame and connected with a bell-crank lever 31 by the pitman 32, the bell-crank lever being connected with the lifting hook by the spiral spring 33. The shafts d and f rotating at a speed ratio of 2 to 1, it will be seen that upon every other lifting 100 movement of the lifting hook (there being one such movement following each beating-up movement of the lay) the lifting hook will be shifted by spring 27' into position to lift the left-hand jack 21 and upon the remaining movements will be shifted from cam 29 into position to lift the right-hand jack 21. Thus the harnesses rise and fall alternately, the weave produced in the present case being a plain tabby. 105

Shuttles.—The type of shuttle used includes a cylindrical shell 34, closed at both ends except as hereinafter noted, having approximately half of its cylindrical wall forming a hinged cover and having a bow 115 35 on the other half provided with superposed eyelets 36; projecting inwardly from one side of the bow is a novel tension device in the form of a helical spring 37 fitted at one end over a stud 38 on the bow and having at its free end a gilding eyelet 39. The thread extends from the filling package through one eyelet 36 then through the eyelet 39 and then through the other eyelet 36, the spring 37 obviously yielding to preserve 120 the tension uniform. Adjoining the bow the shell 34 has an opening 34' through which the thread extends. At its right-hand end the shell has a headed stud 38, its head being formed conical or rounded; at the 130

other end the shell has a hole 38'. The core of the filling package 40 is a tube 41 longitudinally slotted and containing a thrust-pin or detector 42 which a spiral spring 43, 5 also contained in the tube, tends to cause to protrude from a suitable hole 43' in the left-hand end of the tube and (when the tube is housed in the shell, with its ends resting in sockets 44 provided therefor therein) 10 from the hole 38' of the shell. The detector has a beveled fin 45 protruding from the slot of the tube. When the tube is wound with filling the detector is held retracted (Fig. 17) thereby, it being allowed to protrude from the shell only when the filling has been so far used up that it no longer can 15 resist the pressure of the spring 43.

Picking motion and filling replenishing.—At the left of the loom, opposite the 20 front standard *b*, is a magazine consisting of two uprights 46 upstanding from a bracket 47 bolted to the frame, the same having vertical ways 48 in their adjoining faces and the front one having slits 49 (Fig. 25 11) entering to its way. The magazine is open at the top and bottom, and into it from the top is adapted to be entered a stack of receivers each carrying a shuttle and constructed as follows: The base of each receiver 30 is a flat rectangular block 50 which engages at its vertical edges in the ways 48, preferably having its two forward corners beveled, as shown in Fig. 11. Projecting from the inner face of the block is a socket 35 51 of a diameter to receive, more or less snugly, the left-hand end of a shuttle. The socket has a spring-pressed shoe 52 to bear against said end of the shuttle and hold the latter by slip-friction therein. The block 40 has a hole 53 through which the shuttle detector 42 may protrude.

The shuttle-carrier comprises a horizontal transverse rod 54 adapted to reciprocate in brackets 55 on the front standard *b* and a cylindrical socket 56 secured to the left-hand end of said rod and slotted at the front to accommodate the bow of the shuttle. The right-hand end of the rod is suitably connected to the picking stick 57 which is connected with stud 58 by the link 58. There is always one receiver (the lowest in the stack) directly opposite the shuttle-carrier. Fulcrumed in the socket 56 and in an arm 59 carried by the rod 54 (Figs. 7 to 10) is 55 a locking rod 60, the end of which within the socket forms a crank 61 to interlock with the head of stud 38 on the shuttle; the locking rod also carries a forked crank 62 which embraces rod 54 (so that the rocking 60 movement of the locking rod is limited) and which is connected by the spring 63 with arm 59 so that crank 61 is normally held in position to interlock with stud 38. Back of the shuttle carrier there is ful-

crumed on front standard *b* a cam-shoe 64 which on the alternate left-hand thrusts of the shuttle-carrier is held forward in the path of the crank 62, thus to rock the locking-rod out of locking position as the carrier moves to the left. The pressure required 70 to hold the cam-shoe in position to rock the locking rod is effected by a crank 65 connected therewith, the crank being actuated through link 66 from a lever 67 engaging a cam 68 on shaft *f*. (Levers 30 and 67 75 are fulcrumed in a bracket 69 on a fixed shaft 70. Figs. 1 and 4).

Following a beating-up and on the opening of the shed the shuttle-carrier performs a thrust to the left and (locking-rod 60 being then uninfluenced by the shoe) receives the waiting shuttle in its socket and, the interlock or coupling being effected by crank 61 riding over the conical end of the stud 38 and engaging back of it, carries it 80 to the right. Beating up again occurring upon the shuttle having cleared the shed at the right, on the next opening of the shed the shuttle-carrier performs another thrust to the left and back, at its left-hand limit 90 leaving the shuttle deposited in the receiver due to shoe 64 this time rocking the locking-rod and holding it so that its crank 61 cannot interlock with the shuttle stud. In other words, on its alternate thrusts the shuttle-carrier picks up and carries the shuttle to 95 the right and back, and on the remaining thrusts leaves it deposited in the receiver.

The stack of receivers is supported by one or the other of a pair of thrust checks 71 100 sliding in the slits 49 of the magazine and pivoted at the opposite ends of a rocker 72 which is fulcrumed in a bracket 73 projecting from the magazine (Fig. 3) and has a notched arm 74; a spring 75 coiled about 105 the upper check between a collar thereon and the magazine holds the parts 71 72 normally in the position shown in Fig. 11, where the lower check protrudes into the magazine and supports the receiver-stack. 110 If the arm 74 be depressed the withdrawal of the lower and introduction of the upper check will obviously result in the lowest receiver being allowed to fall from the magazine (76, Fig. 2, being a hopper to receive it) while the remainder of the stack stands supported by the upper check; on the return movement of the rocker, the remainder of the stack will fall into engagement with and be supported by the lower 115 check. The first of these movements of the rocker is effected by a hook 77 having a universal connection 78 with a crank 79 on a rock-shaft 80 journaled in suitable bearings at the left of the frame, said hook 120 being normally pressed back, so as not to catch the arm, by a light spring 81. The rock-shaft has a crank 82, which, by a link

83, is connected with a lever 84 engaging a cam 85 on shaft *f*. The hook moves down and back on every other pick of the loom (*i. e.*, when the shuttle remains in its receiver) and so long as the filling lasts it descends without actuating the checks, thus: A two-armed lever 86—87, the arms of which are yieldingly connected by the spring 88 so that one can swing without movement of the other, is fulcrumed on the stud 89 projecting laterally from the magazine (see Fig. 4). The inner arm 86 of this lever plays across the hole 53 of the lowest receiver (Fig. 11) and if the detector of the corresponding shuttle projects from said hole said arm will be prevented thereby from descending with the other arm. There is a bend forming a cam-face 90 in the hook so situated that if the hook descends while the arm 86 is thus prevented from descending the hook will be cammed over, and so carry down with it, the arm 74 of the rocker, but will remain clear of said arm 86 if the latter also descends. The lever 86—87 is rocked down and back substantially in consonance with the down and up movements of the hook through a link 91 connecting its arm 87 with a crank 92 on a sleeve 93 arranged on the rock-shaft 80, said sleeve carrying a crank 94 which is connected by a link 95 with a lever 96 engaging a cam 97 on shaft *f*. (Levers 84 and 96 are fulcrumed in a bracket 98 on shaft 70—Figs. 2 and 4—and they are connected with an extension 99 of said bracket—Figs. 1 and 3—by a spring 100 holding them against their cams.)

Drive shaft *c* carries fast and loose pulleys 101 to receive a driving belt controlled by the belt shifter 102.

Operation.—As explained, from face plate *h* the lay structure obtains a movement which produces what is in effect a whipping-up of the filling to the fell of the cloth, the lay structure moving at accelerated speed forward and at slowing speed backward; substantially the same kind of movement is imparted to the warp to change the shed, since the lifting hook 26 derives its motion also from the same means as the lay-structure (raising and lowering in alternation the two parts of the warp to form the shed, due to the lifting hook being swung alternately to right and left on descending, so as to lift first one and then the other harness jack 21). The upper half of the warp descends to the plane of the lower half to close the shed substantially simultaneously with the reed reaching its full forward position.

The picking motion occurs in alternation with the closing of the shed, since face plate *h'* obviously rotates reversely to face plate *h* and wrist pin *j'* is passing over while wrist pin *j* is passing under the center of move-

ment. As explained, the advance part of the picking movement is accelerating and its retracting part slowing in character, the same as in the case of the beating-up motion.

As to each complete cycle of movement of the two means—beating up and picking—each begins while the other is in progress (to wit, about half-way of the cycle), so that time is saved and the wear and tear and vibration are reduced, especially as the speed variance in each instance is gradual in character.

Every other time the shuttle-carrier reaches its left-hand limit of motion it picks up the shuttle, leaving it in the receiver the remaining times, the cam-shoe 64 alternately preventing and failing to prevent automatic interlocking of the shuttle and receiver on succeeding picks due to its active state being established (from shaft *f*) intermittently on each two cycles of picking movement.

So long as the detector of the working shuttle remains held retracted by the filling its receiver 51 remains co-operatively aligned with the shuttle carrier. But whenever the filling of such shuttle fails, and the shuttle therefore is left in its receiver with its detector protruding, said shuttle and its receiver are ejected and a fresh receiver and shuttle come into action thus: Hook 77 and lever 86—87 derive their downward impulses (from cam shaft *f*) every two picks—when the shuttle is in the receiver. The detector of the spent shuttle being in obstructing relation to lever arm 86, when the hook descends it is cammed by said arm over and engages the arm 74 (which at any other time it would miss), so that the rocker is first moved one way and then (under influence of spring 75) the other, the spent shuttle and its receiver being delivered into hopper 76 and a fresh shuttle and receiver coming into co-operative relation to the shuttle carrier in the way already explained.

Each element *k* *k'* serves as means to confine the free end of the pitman *i* (*i'*) to a path of oscillating movement. There is another feature of this mechanism, however, which affects the action of the means to be actuated, and that is the fact that the path of oscillating movement of the free end of the pitman is relatively offset at the end thereof remote from the driver *h* (or *h'*) due to the path being an arc around the fulcrum of *k* (or *k'*) as a center, being offset in the present case in the direction of the acting thrust of the actuated means, so that the whipping motion is obviously accentuated.

Having thus fully described my invention, what I claim as new and desire to secure by Letters Patent is:

1. In a loom, the combination of a ro-

- tating driving element, a motion-transmitting pitman pivoted at one end to an eccentric point of said element and approximating in length the length of the radius 65
 5 from the center to said point of said element, a back-and-forth moving means controlling a part of the material being woven and operatively connected to the free end of said pitman, and means to confine the free end 70
 10 of the pitman to a path of oscillatory movement extending away from said element.
2. In a loom, the combination of a rotat- 75
 ing driving element, a motion-transmitting pitman pivoted at one end to an eccentric point of said element and approximating in length the length of the radius from the center to said point of said element, a back-and- 80
 15 forth moving means controlling a part of the material being woven and operatively connected to the free end of said pitman, and means to confine the free end of the pitman to a curved path of oscillatory movement extending away from said element. 85
 20
3. In a loom, the combination of a rotat- 90
 ing driving element, a motion-transmitting pitman pivoted at one end to an eccentric point of said element and approximating in length the length of the radius from the center to said point of said element, a back-and- 95
 25 forth moving means controlling a part of the material being woven and operatively connected to the free end of said pitman, and pivoted means to confine the free end of the pitman to a curved path of oscillatory movement extending away from said element. 100
 30
4. In a loom, the combination of a rotat- 105
 ing driving element, a motion-transmitting pitman pivoted at one end to an eccentric point of said element and approximating in length the length of the radius from the center to said point of said element, a back-and- 110
 40 forth moving means controlling a part of the material being woven and operatively connected to the free end of said pitman, and means to confine the free end of the pitman to a path of oscillatory movement extending away from said element and having its outer end relatively offset in the direction of the acting thrust of said controlling means. 115
 45
5. A weaving apparatus including, with instrumentalities to support and advance the warp and form therein the shed, and a filling carrier movable forward and back through the shed, means to move the carrier from one side of the warp to the other and back at accelerating speed approximately to the limit of its movement in the forward direction. 120
 50
6. A weaving apparatus including, with instrumentalities to support and advance the warp and form therein the shed, a filling carrier movable forward and back through the shed, and a reed movable forward and back to and from the cloth, means to move the carrier and reed simultaneously in relatively opposite directions and each at accelerating speed in the forward direction. 125
 60
7. A weaving apparatus including, with instrumentalities to support and advance the warp and form therein the shed, a filling carrier movable forward and back through the shed, and a reed movable forward and back to and from the cloth, means to move the carrier and reed simultaneously in relatively opposite directions and each at accelerating speed approximately to the limit of its movement in the forward direction. 70
 75
8. A weaving apparatus including, with instrumentalities to support and advance the warp and form therein the shed, a filling carrier movable forward and back through the shed, and a reed movable forward and back to and from the cloth, means to move the carrier and reed simultaneously in relatively opposite directions and each at accelerating speed approximately to the limit of its movement in the forward direction. 80
 85
9. In combination, a movable filling-supply, a filling-supply receiver at one side of the warp releasably holding the filling supply, means, located at the other side of the warp and movable through the warp shed toward and from the receiver, to withdraw the filling-supply from the receiver, carry it back and forth and redeposit it in the receiver, and means to reciprocate the first means. 95
 90
10. In combination, a movable filling-supply, a filling-supply receiver at one side of the warp releasably holding the filling-supply, means, including a carrier located at the other side of the warp and movable through the warp shed toward and from the receiver, to withdraw the filling-supply from the receiver, carry it back and forth and redeposit it in the receiver, and means to reciprocate the carrier. 100
 105
11. In combination, reversely movable harnesses controlling the warp, a filling-supply receiver at one side of the warp releasably holding the filling-supply, means, located at the other side of the warp and movable through the warp shed toward and from the receiver, to withdraw the filling-supply from the receiver, carry it back and forth and redeposit it in the receiver, means to reciprocate the first means and means to reversely move the harnesses in alternation with each forward-and-back stroke of the first-named means. 115
 110
12. In combination, a shuttle, a shuttle receiver at one side of the warp releasably

holding the shuttle, means, including a carrier located at the other side of the warp and movable through the warp shed toward and from the receiver, to withdraw the shuttle from the receiver, carry it back and forth and redeposit it in the receiver, and also including a shuttle coupling means for

the carrier, means to reciprocate the carrier, and means to control the shuttle-coupling means.

In testimony whereof I affix my signature.

WILLIAM S. WELLS.
